UNITED STATES PATENT OFFICE

2,628,040

APPARATUS FOR HANDLING COILS OF
STRAND MATERIAL

Vincent A. Rayburn, Baltimore, Md., assignor to
Western Electric Company, Incorporated, New
York, N. Y., a corporation of New York

Application April 9, 1951, Serial No. 219,941

7 Claims. (Cl. 242—78)

1

This invention relates to apparatus for handling coils of strand material, and more particularly to apparatus for handling coreless coils of wire.

In the manufacture of electrical conductors and cables, a wire usually is withdrawn from a supply coil and advanced through various processing apparatus. In some instances the coils of wire are not supplied on a spool or a reel, but are supplied in the form of coreless coils held in the shape in which they are wound by a plurality of thin steel straps, or the like. To use coils wound in this manner with apparatus designed to manufacture electrical conductors and cables, an apparatus must be provided for supporting such coils so that the wire may be withdrawn therefrom under tension, and must hold the coil in a tightly packed condition after the straps are removed so that the convolutions of the coil do not become entangled.

An object of the invention is to provide new and improved apparatus for handling coils of strand material.

Another object of the invention is to provide new and improved apparatus for handling coreless coils of wire.

An apparatus for handling coils of strand material illustrating certain features of the invention may include a rotatable member on which such a coil may be positioned, expandable means provided on the member for locking the coil for rotation with the member, and means attachable to the member for holding the convolutions of the coil tightly together.

Other objects and advantages of the invention will appear from the following detailed description of a specific embodiment thereof, when read in conjunction with the appended drawings, in which:

Fig. 1 is a side elevation of an apparatus embodying certain features of the invention;

Fig. 2 is a side elevation of a portion of the apparatus shown in Fig. 1 which has been actuated to a different operating position and having portions thereof removed;

Fig. 3 is a right end view of the apparatus shown in Fig. 1 with portions thereof broken away;

Fig. 4 is a fragmentary horizontal section taken along line 4—4 of Fig. 3;

Fig. 5 is a vertical section taken along line 5—5 of Fig. 3;

Fig. 6 is a vertical section taken along line 6—6 of Fig. 1;

Fig. 7 is a vertical section taken along line 7—7 of Fig. 1;

2

Fig. 8 is a fragmentary vertical section taken along line 8—8 of Fig. 5;

Fig. 9 is the same as Fig. 8, but showing portions of the apparatus in different positions, and

5 Fig. 10 is a side elevation of a typical coil of wire to be handled by the apparatus shown in Fig. 1.

Referring now to the drawings, and more particularly to Figs. 5 and 7, there is shown an apparatus for handling coreless coils of strand material which includes an elongated shaft 15 mounted rotatably in an end member 16 permanently secured to one end of a cylindrical housing 17, and an end member 18 secured removably

10 to the opposite end of the housing 17 by screws 19—19. The housing 17 is provided with diametrically opposed trunnions 20—20 (Fig. 7) which engage bearings 21—21 so as to mount the housing pivotally with respect to the longitudinal axis

15 of the shaft 15. A worm gear segment 25 is keyed to one of the trunnions 20—20, as seen in Fig. 7, and engages a worm 26 keyed to an output shaft 27 of a gear reducer 31 driven by an electric motor 30.

20 A brake drum 34 (Fig. 5) made of magnetic material, is mounted on a bushing 33 keyed to the shaft 15, and is engaged by brake shoes 35—35 carried by rocker arm 36—36 (Fig. 6) mounted pivotally on lugs 37—37 secured to the inner surface of the housing 17. The brake shoes 35—35 are urged against the drum by compression springs 40—40 positioned between the bottom of retainer cups 41—41 secured on the outer surface of the housing 17 and nuts 42—42 threadedly

25 mounted on the ends of brake rods 43—43 secured pivotally to the ends of the arms 36—36 and extending through the central opening of the springs. The nuts 42—42 are adjusted on their respective rods 43—43 to positions in which the springs 40—40 cause the brake shoes 35—35 to retard the rotation of the drum 34 with a predetermined braking force. The brake shoes 35—35 preferably are made of hard wood, but may be made of leather or other suitable compositions

30 having the requisite coefficient of friction with respect to the surface of the drum 34. The drum 34 also is engaged by a plurality of electromagnetic brakes 46—46 (Figs. 5 and 7) carried by arms 47—47 mounted pivotally on lugs 48—48

35 secured to the inner surface of the housing 17. The brakes 46—46 contain magnetizing coils (not shown) which, when connected to a suitable electric potential, magnetize the brakes and draw them tightly against the surface of the drum 34

40 and prevent rotation of the drum. A torsion spring 49 is positioned between the end of each

45

50

55

55

arm 47 and its associated lug 48 to hold the brakes 46—46 away from the drum when their magnetizing coils are not energized.

A portion of the shaft 15 extends beyond the end member 16 to receive a reel indicated generally at 50 (Fig. 5) designed to support rotatably a coil 51 of wire 52 so that the wire may be withdrawn from the coil. The reel 50 includes a hub 53 secured to a collar 54 formed on the shaft 15, a removable hub 55 positioned adjacent to the end of the shaft 15, and a sleeve 56 journaled in a bearing 57 provided on the hub 53 and a bearing 58 provided in the central bore of the hub 55. The sleeve 56 is designed to leave an annular clearance between the inner surface thereof and the shaft 15.

The hubs 53 and 55 are similar in construction, each having a substantially polygonal periphery forming a plurality of flat sides on which are positioned bars 60—60. The bars 60—60 are secured permanently on the flat surfaces of the hub 53, and are secured on the flat surfaces of the hub 55 by bolts 61—61 (Figs. 3 and 5) which threadedly engage lugs 59—59 secured on the underside of the bars. Each of the bars 60—60 are provided with flanges 62—62 extending along their opposite edges so as to form elongated, radial slots 63—63 between flanges of adjacent bars, which slots are aligned with radial grooves 64—64 provided in the hubs 53 and 55. This arrangement of the hubs and bars provides a rigid cage-like structure forming the drum portion of the reel 50 which is supported principally by the end member 16.

Coil gripping members 65—65 (Figs. 3 and 8) positioned slidably in the radial slots 63—63 each comprise a flat center bar 66 having a half-round bar 67 secured on one edge thereof and a plurality of tubular lugs 68—68 positioned spacedly along the opposite edge thereof as seen in Figs. 5 and 8. The extremities of the bars 66—66 slidably engage the grooves 64—64 provided in the heads 53 and 55 (Figs. 3 and 8). Links 70—70 (Figs. 5 and 8) are connected to the members 65—65 by pins 71—71 inserted in the tubular lugs 68—68, and to collars 72—72 formed on the sleeve 56 by pins 73—73. A head 76 secured on the left end of the reel 50 by screws 77—77 (Figs. 5 and 8), is provided with slots 78—78 for receiving the half-round edge portions of the gripping members 65—65.

A spanner plate 83 is secured on the end of the sleeve 56 adjacent to the head 55, and is provided with levers 84—84 mounted pivotally at opposite corners of the spanner plate and having their respective portions 82—82 (Fig. 4) thereof arranged to engage slots 85—85 provided in the head 55 (Figs. 4 and 5). When the plate 83 is positioned so that the ends 82—82 of the levers 84—84 engage the slots 85—85 (Figs. 3 and 4), the sleeve 56 is so positioned that the links 70—70 push their respective members 65—65 to their outermost positions at which they center the coil on the reel, and grip the inner surface of the coil 51 with sufficient force to cause the reel 50 to be rotated by the coil 51 when the wire 52 is withdrawn from the coil.

This position of the plate 83 positions the pins 73—73 slightly beyond their dead-center positions in a counterclockwise direction as viewed in Fig. 9, so that the pins are not aligned radially with the pins 71—71 which secure the links to the members 65—65 (Fig. 8). This position of the pins 71—71 and 73—73 produces a toggle effect in the links because the resilient action of the coil 75

51 engaged by the members 65—65 tends to lock the sleeve against movement in a clockwise direction and thereby holds the members 65—65 in their outermost positions. When the levers 54—54 are actuated to remove their respective ends 82—82 from the slots 85—85, the plate 83 may be turned in a clockwise direction, as viewed in Figs. 3 and 8, to move the links 70—70 to positions shown in Fig. 9. This movement of the links moves the members 65—65 to their innermost positions, at which positions, the members 65—65 are disengaged from the inner surface of the coil 51.

A head 87 (Fig. 3) is provided with a polygonal opening 88 having a plurality of flat surfaces which slidably engage the outer surface of the bars 60—60, and a plurality of slots 90—90 to slidably receive the ends of the members 65—65. The head 87 has a spider like hub 91 having a central bore 92 (Fig. 5) designed to fit rotatably over a hub 93 of a handwheel indicated generally at 95. A resilient retainer ring 94 is secured in a groove provided on the inner end of the hub 93 to prevent the handwheel from being withdrawn from the hub 91 of the head 87. The handwheel 95 is mounted threadedly on the end of the shaft 15 so that the head 87 may be pressed tightly against the coil 51 positioned on the reel 50 by turning the handwheel 95 to move the head 87 toward the head 76. The hub 93 is slotted at 96 and a pin 97 is positioned in the hub transversely to the slot 96 to provide a means for lifting the head 87 and the wheel 95 assembly from the reel 50. The head 87 is removed from the reel 50 by turning the handwheel 95 until the hub 93 is disengaged from the threaded end of the shaft 15 in order that a coil 51 may be positioned on the reel 50.

The motor 30 is provided for turning the reel 50 about the central axis of the trunnions 20—20 and move the reel 50 from a horizontal position shown in Fig. 1 to a vertical position shown in Fig. 2. When the reel 50 is positioned as shown in Fig. 1, a pin 98 secured to the gear segment 25 holds a spring return limit switch 100 mounted on the bearing 21 positioned adjacent to the gear segment 25 in an open position. When the reel is positioned vertically, as seen in Fig. 2, the pin 98 holds a spring return limit switch 102 also mounted on the bearing 21 in an open position. The motor 30 and the switches 100 and 102 are connected (by means not shown) to a source of electric potential in such a manner that when the pin engages the switch 100, the motor 30 may be energized only to turn the reel 50 about the central axis of the trunnions 20—20 in a counterclockwise direction, when viewed in Fig. 1.

When the pin 98 actuates the switch 102, the motor 30 is deenergized thereby, and the reel 50 is positioned vertically. Operation of the switch 102 prevents further movement of the reel in a counterclockwise direction, but the motor 30 may be energized to turn the reel 50 in a clockwise position through a circuit including the closed switch 103. The reel may be driven in a clockwise direction until the pin 98 actuates the switch 100 to its open position and deenergizes the motor.

When the reel 50 is positioned vertically, the head 87 is removed from the shaft 15 (Fig. 2), in the manner described, in order that the coil 51 (Fig. 10) may be lowered onto the head 76 of the reel. The convolutions of the coil 51 are held together by a plurality of thin, steel straps 103—103 which extend around the body of the

coil and have their ends firmly secured together, whereby the straps 103-103 hold the coil 51 in the shape in which it was wound. To facilitate loading a coil, like the coil 51 on the reel 50, a suitable hoisting mechanism (not shown) having grapple hooks 104-104 may be provided for lifting the coil 51 and positioning it on the reel 50 when the reel is in a vertical position. After the coil 51 is positioned onto the head 76, the hooks 104-104 are removed from the coil, the 10 spanner plate 83 is turned in a counterclockwise direction, as viewed in Figs. 3 and 8, to cause the members 65-65 to grip the coil 51, and the head 87 is attached to the shaft 15 to hold the coil on the reel 50.

The coil 51, shown in Fig. 10, is a traverse wound, coreless coil, that is, the wire 52 is not supplied on a reel or spool which may be used to support the coil when the wire is withdrawn therefrom. The individual convolutions of the coil are bound together by the steel straps 103-103, and these straps must be removed before the wire 52 may be withdrawn from the coil. The individual layers of the coil are in effect, alternating right-hand and left-hand helical springs, and when the head 87 is urged toward the head 76 by the handwheel 95, the layers are compressed until the individual convolutions almost abut each other.

When the coil 51 is secured between the heads 30 76 and 87 in this manner, the steel straps 103-103 are cut and removed from the coil through slots 106-106 provided in the heads 76 and 87.

The surfaces of the heads that engage the ends 35 of the coil slope inwardly slightly so that the heads press the inner layers of the coil more tightly together than the outer layers. By pressing the inner layers of the coil together tightly, the outer convolutions of the wire 52 are prevented from forcing or prying in-between the convolutions of the inner layers when the wire 52 is withdrawn from the coil.

Operation

Assuming that the above-described coil handling apparatus is in a horizontal position as shown in Fig. 1, the motor 39 is connected to a suitable source of power by conventional electrical switching apparatus, not shown, to turn the reel 50 about the central axis of the trunnions 29-29 in a counterclockwise direction until the pin 98 actuates the switch 102 and de-energizes the motor 39. When the switch 102 is actuated to deenergize the motor 39, the reel 50 is in a vertical position, as shown in Fig. 2. The handwheel 95 then is turned until it is free of the threaded end of the shaft 15, and the head 87 then is removed from the reel 50. The levers 84-84 mounted on the plate 83 are raised so that they are perpendicular to the plate 83, as shown in Fig. 2, in which positions, their ends 82-82 are disengaged from their respective slots 85-85. The levers are used to turn the plate 83 and the sleeve 56 connected thereto in a clockwise direction, when viewed in Figs. 3 and 8. Movement of the sleeve 56 in this direction positions the links 70-70, as shown in Fig. 9, and thereby moves the members 65-65 to their innermost positions, as shown in Fig. 9.

A coil of wire, like the coil 51, which is held together by the steel straps 103-103, is lowered onto the head 76 of the reel 50 by means of a hoist, not shown, to which the grapple hooks 104-104 are attached. After the coil is loaded

on the head 76 of the reel 50, the plate 83 and the sleeve 56 connected thereto, are turned in a counterclockwise direction when viewed in Figs. 3 and 8 until the ends 82-82 of the levers 84-84 are positioned over the slots 85-85 provided in the hub 55. The levers 84-84 then are moved inwardly toward the plate 83 and the ends 82-82 of the levers enter the slots 85-85 and lock the plate 83 against movement with respect to the hub 55. This movement of the sleeve 56 moves the members 65-65 outwardly so that the semi-circular edge portions 67-67 of the members engage the inner surface of the coil 51.

When the handles 84-84 are actuated so that 15 their ends completely engage their respective slots 85-85, the movement of the sleeve 56 is such that it carries the pins 73 which connect the links 70-70 to the sleeve 56 in a counterclockwise direction slightly beyond a position in which the pins 73-73 would be radially aligned with the pins 71-71 which connect the links to the members 65-65. This position of the pins 73-73 with respect to the pins 71-71 forms a toggle action between the members 65-65 and the links 70-70 in which the force acting on the members due to their engagement with the coil tends to urge the pins 73-73 in a clockwise direction and thereby prevents rotation of the sleeve in a counterclockwise direction.

After the plate 83 has been actuated to secure the coil 51 tightly on the members 65-65, the head 87 is positioned on the end of the reel 50 and the handwheel 95 is turned to thread the wheel on the end of the shaft 15. As the handwheel is threaded on the end of the shaft, it moves the head 87 toward the head 76 whereby the coil 51 positioned on the reel is compressed between the heads 76 and 87. After the head 87 is secured on the reel 50 in this manner, the straps 103-103 are cut and removed from the coil 51 in order that the wire 52 may be withdrawn from the coil 51.

When the reel 50 is positioned vertically, the electromagnetic brakes 46-46 are energized because they are deenergized only when the wire 52 is being withdrawn from the coil under a predetermined tension. As a result, the brakes 46-46 are drawn magnetically to the drum 34 and prevent the reel 50 from turning when the spanner plate 83 and the handwheel 95 are turned in the above-described manner to secure a coil on the reel. The motor 39 then is energized to turn the reel in a clockwise direction until the pin 98 actuates the limit switch 100 and de-energizes the motor. The reel 50 now is positioned horizontally and supports the coil in a position in which the wire 52 may be withdrawn from the coil 51.

Since the coil 51 is engaged by the members 65-65, the withdrawal of the wire 52 from the coil rotates the shaft 15 in the bearings 16 and 18 through the cage-like structure including the hubs 53 and 55 and the bars 60-60. The springs 40-40 urge the brake shoes 35-35 against the drum with sufficient force to create a predetermined tension in the wire 52 as it is withdrawn from the coil 51. The head 87 is positioned on the reel 50 by the handwheel 95 so as to pack the convolutions of the inner layers of the coil 51 tightly together and prevent the wire 52 from forcing in-between the adjacent convolutions of the inner layers of the coil and becoming entangled therewith.

The electromagnetic brakes 46-46 are rendered inoperative during the period that the

wire is withdrawn from the coil 51 under a pre-determined tension, but if the apparatus withdrawing the wire from the coil should stop suddenly, or if the wire should break as it is withdrawn from the coil, the electromagnetic brakes 46-46 are energized immediately to stop the rotation of the reel 50 and thereby prevent excessive unwinding of the wire from the coil 51.

While the above-described apparatus is particularly well adapted for handling a coreless coil of wire so that the wire is withdrawn therefrom, it may be modified readily to handle coils of various types of filamentary articles without departing from the spirit and scope of the invention.

What is claimed is:

1. An apparatus for handling coils of strand material, which comprises a tubular member having a circular flange secured on one end thereof, means for supporting the member rotatably about its longitudinal axis, said member having a plurality of slots equally spaced about the periphery thereof and designed to fit loosely within the central opening of a coil of strand material, a coil gripping member positioned slidably in each of the slots, a sleeve positioned within the rotatable member and rotatable about the longitudinal axis thereof, a plurality of links connecting the coil gripping members to the sleeve, means for turning the sleeve in one direction to cause the links to move the coil gripping members to their innermost positions within the slots so that a coil may be positioned on the rotatable member and for turning the sleeve in the opposite direction to cause the links to move the coil gripping members to their outermost positions with sufficient force to secure the member for rotation with the coil, a flange positioned slidably on the opposite end of the rotatable member, and means attachable to the rotatable member for moving the last-mentioned flange toward the flange secured on the opposite end of the rotatable member and thereby clamp the coil tightly between the flanges so as to hold the convolutions of the coil together, said coil being clamped between the flanges with sufficient force to prevent the strand material in the outer convolutions of the coil from forcing in-between the convolutions of the inner layers of the material when the material is withdrawn from the coil.

2. An apparatus for handling coils of strand material, which comprises a shaft, means for supporting the shaft rotatably, a substantially tubular member having a circular flange on one end thereof secured on one end of the shaft, said tubular member having a plurality of coil gripping members mounted slidably about the periphery of the tubular members so as to be movable radially with respect to the axis of rotation of the shaft, said tubular member being designed to fit loosely within the central opening of a coil of strand material, means mounted on the shaft for moving the coil gripping members from positions in which they are disengaged from the inner surface of the coil to positions in which they engage the inner surface of the coil with sufficient force to secure the rotatable member for rotation with the coil when the strand material is withdrawn from the coil, a circular flange positioned slidably on the open end of the rotatable member, and means removably attachable to the end of the shaft for urging the movable flange toward the stationary flange and clamp the convolutions of the coil together to prevent the outer convolutions of the strand ma-

erial from forcing in-between the convolutions of the inner layers of the strand material as the strand material is withdrawn from the coil.

3. An apparatus for handling coils of strand material, which comprises a tubular member having a circular flange secured on one end thereof, means for supporting the member rotatably about its longitudinal axis, said rotatable member having a plurality of slots equally spaced about the periphery thereof and designed to fit loosely within the central opening of a coil of strand material, a coil gripping member positioned slidably in each of the slots, a sleeve positioned within the rotatable member and rotatable about the longitudinal axis thereof, a plurality of links connecting the coil gripping members to the sleeve, means for turning the sleeve in one direction to cause the links to move the coil gripping members to their innermost positions within the slots so that a coil may be positioned on the rotatable member and for turning the sleeve in the opposite direction to cause the links to move the coil gripping members to their outermost positions with sufficient force to secure the coil for rotation with the rotatable member, means for locking the sleeve against movement when the coil gripping members engage the inner surface of the coil, a flange positioned slidably on the opposite end of the rotatable member, and means attachable to the rotatable member for moving the last-mentioned flange toward the flange secured on the opposite end of the rotatable member and thereby clamp the coil tightly between the flanges so as to hold the convolutions of the coil together, said coil being clamped between the flanges with sufficient force to prevent the strand material in the outer convolutions of the coil from forcing in-between the convolutions of the inner layers of the material when the material is withdrawn from the coil.

4. An apparatus for handling coils of strand material, which comprises a shaft, means for supporting the shaft rotatably, a substantially tubular member having a circular flange on one end thereof secured on one end of the shaft, said tubular member having a plurality of coil gripping members mounted slidably about the periphery of the tubular members so as to be movable radially with respect to the axis of rotation of the shaft, said tubular member being designed to fit loosely within the central opening of a coil of strand material, means mounted on the shaft for moving the coil gripping members to positions in which they are disengaged from the inner surface of the coil to positions in which they engage the inner surface of the coil with sufficient force to secure the rotatable member for rotation with the coil when the strand material is withdrawn from the coil, a circular flange positioned slidably on the open end of the rotatable member, and means attachable to the end of the shaft for urging the movable flange to the stationary flange and thereby clamp the convolutions of the coil together, said flange having their opposed surfaces inclined toward each other so that they clamp the inner convolutions of the coil tightly together to prevent the outer convolutions of the strand material from forcing in-between the convolutions of the inner layers of the strand material.

5. An apparatus for handling coils of strand material in which the convolutions of the coils are held together by a plurality of steel straps, which comprises a housing, a shaft having a portion thereof journalled rotatably on the housing,

a substantially tubular member secured on the end of the shaft extending beyond the housing and designed to fit loosely within the central opening of such a coil, a circular flange secured on the end of a tubular member adjacent to the housing, said tubular member having a plurality of slots equally spaced about the periphery thereof, a plurality of coil gripping members mounted slidably in the slots, one for each slot, means mounted rotatably on the shaft for moving the coil gripping members from positions from which they are disengaged from the inner surface of the coil to positions in which they engage the inner surface of the coil with sufficient force to secure the shaft for rotation with the coil when the strand material is withdrawn from the coil, a flange designed to be positioned slidably on the opposite end of the rotatable member after a coil has been positioned thereon, and means removably attachable to the end of the shaft for urging the movable flange toward the stationary flange and press the convolutions of the coil together with sufficient force to prevent the outer convolutions of the strand material from forcing in-between the inner convolutions of the coil when the strand material is withdrawn from the coil.

6. An apparatus for handling coils of strand material in which the coils are held together by a plurality of steel straps, which comprises a housing, a shaft having one end thereof journaled in the housing, means for supporting the housing pivotally transversely with respect to the longitudinal axis of the shaft, means for turning the housing about its pivot point from a position in which the longitudinal axis of the shaft is horizontal to one in which the longitudinal axis of the shaft is positioned vertically, a substantially tubular member secured on the end of the shaft extending beyond the housing and designed to fit loosely within the central opening of such a coil, a circular flange secured on the end of a tubular member adjacent to the housing, said tubular member having a plurality of slots equally spaced about the periphery thereof, a plurality of coil gripping members mounted slidably in the slots, one for each slot, means mounted rotatably on the shaft for moving the coil gripping members from positions from which they are disengaged from the inner surface of the coil to positions in which they engage the inner surface of the coil with sufficient force to secure the shaft for rotation with the coil when the strand material is withdrawn from the coil, a flange designed to be positioned slidably on the opposite end of the rotatable member after a coil has been positioned thereon,

and means removably attachable to the end of the shaft for urging the movable flange toward the stationary flange and pressing the convolutions of the coil together with sufficient force to prevent the outer convolutions of the strand material from forcing in-between the inner convolutions of the coil when the strand material is withdrawn from the coil.

7. An apparatus for handling coils of strand material, which comprises a rotatable drum-like member designed to fit loosely into the central opening of such a coil, said member having a plurality of slots spaced about the periphery thereof, a coil-engaging abutment mounted slidably in each of the slots, a sleeve positioned within the drum-like member and rotatable about the longitudinal axis thereof, a plurality of links connecting the coil-engaging abutments to the sleeve, and means for selectively turning the sleeve in one direction to cause the links to move the coil-engaging abutments to their innermost positions within the slots wherein they do not protrude beyond the periphery of the drum-like member and permit a coil to be positioned on said member and for turning the sleeve in the opposite direction to cause the links to move the abutments radially outward to a position wherein they protrude beyond the periphery of the drum-like member and engage the coil with sufficient force to secure it for rotation with said member, a flange secured to one end of the rotatable member, and a second flange positioned slidably and adjustably on the opposite end of the rotatable member for forcing the convolutions of the coil together to prevent the outer convolutions of the coil from forcing in-between the inner convolutions of the coil when the strand material is withdrawn from the coil.

VINCENT A. RAYBURN.
